DESIGN FOR A TOILET ACCESSORIES CONTAINER

Enid Edson, New York, N. Y., assignor to Shulton,
Inc., New York, N. Y., a corporation of New
Jersey

Application May 31, 1940, Serial No. 92,699

Term of patent 3½ years

To all whom it may concern:

Be it known that I, Enid Edson, a citizen of the United States of America, residing in New York city, county of New York, Borough of Manhattan, and State of New York, have invented a new, original, and ornamental Design for a Toilet Accessories Container, of which the following is a specification, reference being had to the accompanying drawings, forming a part thereof.

Figure 1 is a perspective view of a toilet accessories container showing my new design.

Figure 2 is a top plan face view thereof in completely open position.

Figure 3 is a similar view of the outside thereof with the ribbons broken away for convenience of illustration.

Figure 4 is a perspective view in partly folded position, with the two halves forming the top, folded back to disclose the full-size sub-top normally covered by such two halves.

I claim:

The ornamental design for a toilet accessories container, as shown.

ENID EDSON.
